Inventor:

W^m. M. Saunders

By his Attorney
Karl W. Bruegger.

UNITED STATES PATENT OFFICE.

WILLIAM M. SAUNDERS, OF WATERBURY, CONNECTICUT, ASSIGNOR TO THE HOGE MANUFACTURING COMPANY, OF NEW YORK, N. Y., A CORPORATION OF NEW YORK.

PENCIL-CLIP.

1,358,338.

Specification of Letters Patent. Patented Nov. 9, 1920.

Application filed January 15, 1920. Serial No. 351,602.

To all whom it may concern:

Be it known that I, WILLIAM M. SAUNDERS, a citizen of the United States, residing at Waterbury, county of New Haven, 5 State of Connecticut, have invented a certain new and useful Improvement in Pencil-Clips, of which the following is a full, clear, and exact description.

My invention relates to a new and improved pencil clip and has for its object to provide a lift clip having a spring arm with a lifting lever secured to the outside thereof, said lifting lever and spring arm being of approximately the same width at all 15 points where they are adjacent and tapering so as to present a neat and attractive appearance. A further object of my invention is to produce a pencil clip which is simple to manufacture and durable in construction, 20 and to avoid the clumsy appearance which results from having the body of one of the two members mentioned pass through the body of the other.

The following is a description of a pencil 25 clip embodying my invention, reference being had to the accompanying drawings, in which,

Fig. 1 shows a side elevation of a clip embodying my invention;

30 Fig. 2 shows a section of the same on the line 2—2;

Fig. 3 shows on a reduced scale the lift lever in two stages of manufacture;

Fig. 4 shows in detail the spring arm and 35 pencil clamp separate from the lifting arm.

Referring more particularly to the drawings, 1 is a pencil clasping portion which has formed integral therewith a forwardly projecting spring arm 2 having near its rear 40 end a perforation 3 and upon its forward end a slightly dished circular head portion 4 connected to the body of the spring arm by a narrowed neck 4'. 5 is a lifting or releasing lever from the medial portion of 45 which a slight downwardly projecting prong 6 is struck up, the same being passed through the perforation 3 in the spring arm and bent over so as to rivet the two parts together at that point. In order to hold the 50 forward ends of the two parts together, the releasing arm is provided at its end with a ball 7 within which the circular head portion 4 of the spring lever is embraced so as to be firmly held therein.

In making this ball the blank is first 55 struck out so as to have four arms 8, as shown at the top in Fig. 3; these arms are then bent into parallel relation, as shown at the center in Fig. 3 and the prong 6 formed, after which the end 4 of the spring 60 arm is laid therein, the prong 6 on the lifting lever being passed through the perforation 3 in the spring arm. The radiating portions 8 are then bent down over the circular portion 4 of the spring arm so as to 65 embrace it firmly and form a ball, while the prong 6 on the lifting arm is bent backward so as to secure the rear end of the spring arm to the lifting arm. In order to provide further finish, and also to hold the 70 two parts more firmly together, the lifting arm is provided with two downwardly turned flanges 9 forming a channel in which the spring arm lies, these flanges being formed from the parts 9' in Fig. 3. 75

In this way a lift pencil clip is provided in which the body of neither member passes through the other so that no enlargement is necessary, the spring arm and lifting arm being substantially parallel at all points of 80 contact, the inner one lying within a channel in the outer so as to help define their relations and improve the appearance of the finished clip; also a clip in which the lifting arm tapers from one end to the other so as 85 to present a pleasing appearance. The clip is also simple to manufacture and of durable construction. The clip is released in the ordinary manner by pressing on the extension at the rear end of the lifting lever. 90

As will be evident to those skilled in the art, my invention permits of various modifications without departing from the spirit thereof or the scope of the appended claims. 95

What I claim is:

1. In a pencil clip, the combination of a pencil clasping portion having integral therewith an offset forwardly projecting spring arm, a lifting lever in contact with the outer side of said spring arm and rigidly secured thereto at a point adjacent to its rear end and having its forward end rigidly secured to the forward end of said spring arm, said spring arm and said lifting lever being substantially parallel between the points at which they are secured together. 100

105

2. In a pencil clip, the combination of a pencil clasping portion having integral therewith an offset forwardly projecting spring arm, a lifting lever in contact with 5 the outside of said spring arm and rigidly secured thereto at a point adjacent to its rear end and having its forward end secured to the forward end of said spring arm, said spring arm and said lifting lever being 10 substantially parallel between the points at which they are secured together, said lifting lever having a hollow ball inclosing the forward end of said spring arm and constituting the means for securing said forward 15 ends together.
3. In a pencil clip, the combination of a pencil clasping portion having integral therewith an offset forwardly projecting spring arm, a lifting lever in contact with 20 the outer side of said spring arm and rigidly secured thereto at a point adjacent to its rear end and having its forward end secured to the forward end of said spring arm, said spring arm and said lifting lever 25 being substantially parallel between the points at which they are secured together, said lifting lever having a hollow ball in-
- closing the forward end of said spring arm, the portion of said spring arm within said ball being connected to the body of said 30 spring arm by a reduced portion.
4. In a pencil clip, the combination of a pencil clasping portion having integral therewith an offset forwardly projecting spring arm, a lifting lever riveted to the 35 outer side of said spring arm at a point adjacent to its rear end and having its forward end secured to the forward end of said spring arm, said spring arm and said lifting lever being substantially parallel 40 between the points at which they are secured together.
5. In a pencil clip, the combination of a pencil clasping portion having integral therewith an offset forwardly projecting 45 spring arm, a lifting lever in contact with the outer side of said spring arm and rigidly secured to said arm at a point adjacent to its rear end and having its forward end secured to the forward end of said spring 50 arm, said lifting lever having depending flanges lying on each side of said spring arm.

WILLIAM M. SAUNDERS.
